DISPLAY PACKAGE FOR JEWELRY

George B. Nathanson, Brookline, Mass.

Application September 18, 1935, Serial No. 41,143

4 Claims. (Cl. 206—44)

This invention relates to a display package for jewelry.

An object of my invention is to provide a display box, preferably of ornamental design whereupon to arrange and display a piece of jewelry such as for an example a finger ring, or a watch, preferably in connection with an ornamental gift card.

Another object of my invention is to provide such a device which is simple in structure and attractive in appearance.

The foregoing and other objects of my invention will be best understood from the following description of an exemplification thereof, reference being had to the accompanying drawing, wherein:

Fig. 1 is an exploded perspective view of the elements of one form of my novel box;

Fig. 2 shows the elements of Fig. 1 in their assembled form;

Fig. 3 shows a supporting element which is to be placed in the box of Fig. 2;

Fig. 4 shows a card supporting a piece of jewelry which card is adapted to be placed upon the supporting member of Fig. 3;

Fig. 5 shows a gift card which is adapted to be superimposed on the card shown in Fig. 4, when supported in the box of Fig. 2;

Fig. 6 represents a cover which is adapted to be placed over the complete box.

In the drawing, 1 represents a box having a bottom 2 with side walls 3 and front and back walls 4 and 5. The side walls 3 are cut with their upper sides at an angle and the back wall 5 is taller than the front wall 4; thus giving a slant to the top of the box. Within the portion formed by the walls 3, 4, and 5, the inner receptacle portion 6 is adapted to be glued to the bottom 2. The inner receptacle portion 6 is likewise formed with the bottom 7, side walls 8, front and back walls 9 and 10. The side walls 8 are cut to the same angle as the side walls 3 of the box 1 and are of such a height that when assembled within the box 1, the upper edges of the side walls are substantially the same height as the upper edges of the side walls 3. When the inner receptacle portion 6 is assembled within the box 1, there is a space between the walls of the inner receptacle 6 and the walls of the box 1. This space is adapted to be filled by a spacer member 11. This spacer member 11 is provided with the top wall 12, having an opening 13 of the same size as the outside dimensions of the inner receptacle 6. The spacer 11 is, also, pro-

vided with side walls 14 and front and back walls 15 and 16 as shown in Fig. 1.

The box 1, the inner receptacle portion 6 and the spacer 11 are assembled and glued together so as to form the assembly as shown in Fig. 2. In order that the piece of jewelry may be supported within the box, in proper relationship thereto, a supporting member 17 as shown in Fig. 3 is provided, which member is adapted to fit snugly within the walls of the inner receptacle portion 6. This supporting member 17 is provided with a top supporting wall 18, side walls 19 and front and back walls 20 and 21. The side walls 19 are likewise cut at an angle similar to that of side walls 3 so that when the supporting member 17 is inserted within the receptacle portion 6, its upper wall 18 lies substantially at the level of the dotted lines 22 and 23 as indicated in Fig. 2.

In order to support a piece of jewelry such as for example, a ring 24 I provide a card 25 such as shown for example in Fig. 4. This card is provided on its upper surface the same suitable supporting means such as a fabric pad 26 provided with a slot 27 in which the ring 24 may be inserted. The supporting means of pad 26 is preferably disposed at one side of the card 25, leaving the rest of the card with an uninterrupted surface upon which, if desired, a suitable gift design may be printed. Such a gift design is indicated at 28. The card 25 carrying the piece of jewelry 24 is then inserted within the walls of the receptacle portion 6 and is supported by the upper wall 18 of the supporting member 17. The card 25 is preferably of such a size as to fit snugly within the walls of the receptacle 6.

The upper edges of the walls of the box 1, the upper edges of the walls of the receptacle 6 and the upper surface 12 of the spacer 11 are preferably decorated in contrasting colors so that the box assembly of Fig. 2 presents the appearance of a picture frame around the card 25, carrying the piece of jewelry 24 upon it. The resulting display, while simple, presents a very attractive appearance. Instead of imprinting the gift or greeting design directly upon the surface of the card 25, I prefer to leave that surface blank and superimpose upon the assembly a separate gift or greeting card 29 as shown for example, in Fig. 5. This card has some suitable gift or greeting design imprinted upon its surface as shown at 30. In order that the card 29 may be readily assembled and removed from the display, it is provided with an opening 31 formed

therein at such a place that when assembled within the box 1 the piece of jewelry 24 supported on the card 25 passes through said opening 31 so that the card 29 lies flat upon the surface of the underlying card 25. Due to the fact that the card 29 is readily removable from the display assembly, a purchaser of the article can select any card which he may choose. It is contemplated that a relatively large number of separate cards 29 bearing different designs on their surface be provided in order that a selection may be made therefrom. I, also, prefer to have the card 25 as well as the card supporting member 17 readily removable from the assembly.

15 Although the assembly is adapted to be displayed without a cover, I, also, provide a suitable cover 32 such as that, for example, shown in Fig. 6 so that when the display article is sold, the cover 32 may be placed around the side walls of the box 1, resting upon the bottom wall 2 and thus forms a complete package, which is readily transportable.

This invention is not limited to the particular details of construction described above as many equivalents will suggest themselves to those skilled in the art. It is accordingly desired that the appended claims be given a broad interpretation commensurate with the scope of the invention within the art.

30 What is claimed is:

1. A display package comprising a box having upstanding side walls, a receptacle member within said walls, said receptacle member also having upstanding side walls, a spacing member substantially filling the spaces between the side walls of said box and receptacle member, a supporting member within said receptacle member, the said supporting member having a supporting surface slightly below the top of the side walls of said receptacle member, a sheet member supported on said supporting surface, a piece of jewelry supported adjacent a restricted portion of said sheet member, the remaining portion of said sheet member having placed upon its surface a gift or greeting inscription.

2. A display package comprising a box having upstanding side walls, a decorative frame portion within said box comprising a receptacle member within said side walls, said receptacle

member also having upstanding side walls and a spacing member substantially filling the spaces between the side walls of said box and said receptacle member, a supporting member within said receptacle member, said supporting member having a supporting surface slightly below the top of side walls of said receptacle member, a sheet member supported on said supporting surface, a piece of jewelry supported upon said sheet member, an additional sheet member superimposed and supported upon said first named sheet member, said additional sheet member having an opening therein through which said piece of jewelry projects, said additional sheet member having upon its surface a gift or greeting inscription.

3. A display package comprising a box having upstanding side walls and a flat base portion, the upper edges of said side walls lying in a plane at an angle with respect to said base portion, a receptacle member within said side walls, said receptacle member also having upstanding side walls, the upper edges of which lie in a similar plane at an angle with respect to said base portion and a spacing member substantially filling the spaces between the side walls of said box and receptacle member, a supporting member within said receptacle member, said supporting member having a supporting surface slightly below the top walls of said receptacle member and lying in a similar plane at an angle with respect to said base portion, a sheet member supported on said supporting surface, a piece of jewelry supported adjacent a restricted portion of said sheet member, the remaining portion of said sheet member having placed upon its surface a gift or greeting inscription.

4. A display package comprising a box, a supporting display surface within said box, a piece of jewelry removably mounted in a definite position on said display surface, a separate, independent greeting card superimposed and removably supported upon said first-named display surface, said greeting card having an opening therein through which said piece of jewelry projects and through which it may be freely drawn from its mounting means.

GEORGE B. NATHANSON.
